PACKAGE OR CONTAINER

Kenneth T. Buttery, Kalamazoo, Mich., assignor
to Sutherland Paper Company, Kalamazoo,
Mich.

Application February 20, 1943, Serial No. 476,575

10 Claims. (Cl. 229—14)

This invention relates to improvements in packages or containers.

The main objects of this invention are:

First, to provide an improved package which is well adapted for use in the packaging and dispensing of food products such as butter, lard, oleomargarine and like greasy or oily products, effectively packaging the contents for delivery and transportation and at the same time one which may be readily opened for access to the 10 packaged product.

Second, to provide a container having these advantages which facilitates the packaging steps.

Objects pertaining to details and economies of the invention will definitely appear from the 15 description to follow. The invention is defined in the claims.

A structure which embodies the features of the invention is clearly illustrated in the accompanying drawings, in which:

Fig. 1 is a top perspective view of a closed package in accordance with a preferred embodiment of my invention.

Fig. 2 is a perspective view with the package partially opened.

Fig. 3 is a perspective view of the inner container member with the top closure flaps of the inner container member and the contents bag arranged therein in fully open position.

Fig. 4 is a fragmentary perspective view with the top of the inner container member and bag in partially closed position.

Fig. 5 is a top perspective view of the top of the outer container member with the top closure flaps partially closed.

Fig. 6 is an enlarged sectional view on line 6—6 of Fig. 1 showing the relation of the bag, the inner container member, the outer container member and one of the retaining tongues for the inner container member.

Fig. 7 is a perspective view of the outer container member in inverted position with the bottom closure flaps open preparatory to receiving the inner closure member with the bag and contents therein.

Fig. 8 is an end view of the container or package fully closed.

Fig. 9 is a perspective view illustrating the final closing step of the top closure.

Fig. 10 is a plan view of a slightly modified form of end closure.

Fig. 11 is a fragmentary perspective view showing a modified form of retaining tongue on the inner container member with the inner container

and bag flaps partially closed and a modified form of top closure flaps.

Fig. 12 is a fragmentary perspective view of a structure embodying the modified form of retaining tongues or lugs on the inner container member, the outer container member being substantially the same as shown in Fig. 11, illustrating another manner of assembling the inner container member within the outer container member.

Fig. 13 is a plan view of the blank of the outer container member.

Fig. 14 is a plan view of the blank for the inner container member.

Fig. 15 is a fragmentary plan view of the blank showing the modified form of retaining tongue or lug.

Fig. 16 is a fragmentary perspective view showing the relation of the end closure flaps in partially closed position.

The preferred embodiment of the invention comprises an outer container member designated generally by the numeral 1, an inner container member designated generally by the numeral 2, and a bag or liner member 3 of flexible material arranged within the inner container member. This bag 3 is preferably of greaseproof material adapted to receive a predetermined quantity of the material to be packaged such as butter, lard, oleomargarine or the like.

The outer container member comprises side walls 4 and end walls 5 provided with overlapping bottom and top closure flaps. These bottom and top closure flaps are of the overlapping interlocking type, the top closure flaps of the embodiment shown in Figs. 1 to 6 comprising the inner flap 6 having a slit 22 parallel to the edge thereof and a slit 23 extending from the slit 22 to the edge. The intermediate flaps 8 are cut away on one edge at 9 to provide an opening through which the dovetail shaped tongue 11 may be engaged when the container is completely closed as shown in Fig. 1. The dovetailed tongue is engaged in the slot 22. In 45 the bottom closure of the outer container of the embodiment illustrated, the flap 21 is provided with a recess 7 in the inner edge thereof so that when the flaps 8 are closed upon it, the tongue 10 of the flap 24 may be readily inserted 50 and interlocked with the edges of the inner flaps 8, as shown in Fig. 8. The side and end walls are provided with fracturing lines 12 disposed in spaced relation to the top end.

The inner container member is adapted to telescope within the outer container member and has

tongues 13 struck out from the bottom of the side and end walls 14 and 15 so that when the inner container member is telescoped within the outer the tongues serve as retaining lugs or detents engaging the wall of the outer member as shown in Fig. 6.

The inner container member is provided with non-overlapping opposed top flaps 16. The bag is of such length that when it is arranged within the container member it projects a substantial distance above the upper edges of the flaps 16 when they are in open position. The flaps 16 may be folded inwardly upon the opposed sides of the bag which results in collapsing these sides and bringing the opposed edges 17 of the bag into side by side relation, projecting from between the flaps 16, see Fig. 4. The collapsed projecting portions 17 are then folded down upon one of the flaps 16 and the end portions 18 are folded inwardly as shown in Fig. 2, thus completely closing the bag and the inner container member, the product packaged having been previously placed within the bag. The inner container member thus closed may then be telescoped within the outer container member, being introduced through either end thereof, and the closure flaps at the ends of the outer container member through which the container is introduced then closed. Care should be taken however that the folded end of the bag and the top closures of the inner container member are at the top end of the outer container member.

When it is desired to have access to the contents the outer container member may be fractured along the fracturing line 12 and the portion thereof above the fracturing lines removed as shown in Fig. 2. This removed portion constitutes a cap 19 which may be replaced, the portion of the inner container member projecting above the fracturing line of the outer container member constituting a neck 20 with which the severed part 19 may be removably engaged.

In the embodiment shown in Figs. 11 and 12 the retaining tongues or lugs 26 are struck out from the walls adjacent the corners thereof. In this embodiment the end closure flaps of the outer container comprise the opposed inner members 27 and the interlocking outer members 28 which have opposed co-engaging tongues 29. The inner container member is the same as described with the exception of the forming and positioning of the retaining lugs.

Fig. 14 is a blank of the inner container member, the bottom closure flaps of which are substantially the same as the top closure flaps of the outer container member shown in Fig. 5.

The inner and outer container members may be made of such relative dimensions that they are easily telescoped and at the same time, owing to the retaining tongues or lugs, they are effectively retained in telescoped relation. This is a feature of great advantage in making up the package. The inner liner or bag 3 can be made of relatively light material and if desired can be easily sealed when the parts are brought into the relation shown in Fig. 4. However, the bag is effectively closed when top of the bag is folded or closed as shown in Fig. 2 and this has the advantage of making it possible to readily open and reclose the bag as occasion requires for removing the contents after the outer container has been fractured along the fracturing lines as shown in Fig. 2.

While this container is especially desirable for use in packaging relatively heavy materials

such as lard, oleomargarine and the like, it is desirable for various other uses. I have illustrated and described embodiments which I have found very practical, and have not attempted to illustrate other adaptations as it is believed this disclosure will enable those skilled in the art to embody or adapt my invention as may be desired.

Having thus described the invention what I claim as new and desire to secure by Letters Patent is:

1. In a package, the combination of an outer container member comprising side walls and overlapping and interlocking bottom and top closure flaps, the side walls having aligned fracturing zones adjacent to but spaced from the top end thereof, an inner container member comprising side walls and overlapping and interlocking bottom closure flaps and opposed non-overlapping top closure flaps, said inner container member being adapted to be telescoped within the outer container member and having projecting tongues struck out from its side walls adjacent the bottom closure flaps constituting bendable retaining members coacting with walls of the outer container member for retaining the inner container member in telescoped relation therein, and a bag of flexible material inserted in said inner container member with its top end when open projecting substantially beyond the said inner container member top closure flaps whereby said top closure flaps may be folded oppositely upon the sides of the bag to collapse the same inwardly with portions thereof projecting from between the edges of the folded top closure flaps and in side by side relation, the said projecting portions being folded upon one of the top closure flaps and the collapsed portions projecting at the ends of said top closure flaps being folded inwardly over the end edges thereof, the end closure flaps of the outer container being in overlapping interlocking position over the closed bag, the outer container member being fracturable along said fracturing lines to permit access to the contents of the package without opening said outer container top closure flaps, the portion of the inner container member projecting above the fracturing zone of said outer container member constituting a neck for detachably receiving the severed portion of the outer container which constitutes a removable cap.

2. In a package, the combination of an outer container member comprising side walls and overlapping and interlocking bottom and top closure flaps, an inner container member comprising side walls and overlapping and interlocking bottom closure flaps and opposed non-overlapping top closure flaps, said inner container member being adapted to be telescoped within the outer container member and having projecting tongues struck out from its side walls adjacent the bottom closure flaps constituting bendable retaining members coacting with walls of the outer container member for retaining the inner container member in telescoped relation therein, and a bag of flexible material inserted in said inner container member with its top end when open projecting substantially beyond the said inner container member top closure flaps whereby said top closure flaps may be folded oppositely upon the sides of the bag to collapse the same inwardly with portions thereof projecting from between the edges of the folded top closure flaps and in side by side relation, the said

projecting portions being folded upon one of the top closure flaps and the collapsed portions projecting at the ends of said top closure flaps being folded inwardly over the end edges thereof.

3. In a package, the combination of an outer container member comprising side walls and overlapping and interlocking bottom and top closure flaps, the side walls having aligned fracturing zones adjacent to but spaced from the top end thereof, an inner container member comprising side walls and overlapping and interlocking bottom closure flaps and opposed non-overlapping top closure flaps, said inner container member being adapted to be telescoped within the outer container member and having projecting tongues struck out from its walls adjacent the bottom closure flaps constituting retaining members coacting with walls of the outer container member for retaining the inner container member in telescoped relation therein, a bag of flexible material inserted in said inner container member with its top end when open projecting substantially beyond the said inner container member top closure flaps whereby said top closure flaps may be folded oppositely upon the sides of the bag to collapse the same inwardly with portions thereof projecting from between the edges of the folded top closure flaps and in side by side relation, the said projecting portions being folded upon one of the top closure flaps and the collapsed portions projecting at the ends of said top closure flaps being folded inwardly over the end edges thereof, the end closure flaps of the outer container being in overlapping interlocking position over the closed bag, the outer container member being fracturable along said fracturing lines to permit access to the contents of the package without opening said outer container top closure flaps, the portion of the inner container member projecting above the fracturing zone of said outer container member constituting a neck for detachably receiving the severed portion of the outer container which constitutes a removable cap.

4. In a package, the combination of an outer container member comprising side walls and overlapping and interlocking bottom and top closure flaps, an inner container member comprising side walls and overlapping and interlocking bottom closure flaps and opposed non-overlapping top closure flaps, said inner container member being adapted to be telescoped within the outer container member and having projecting tongues struck out from its walls adjacent the bottom closure flaps constituting retaining members coacting with walls of the outer container member for retaining the inner container member in telescoped relation therein, and a bag of flexible material inserted in said inner container member with its top end when open projecting substantially beyond the said inner container member top closure flaps whereby said top closure flaps may be folded oppositely upon the sides of the bag to collapse the same inwardly with portions thereof projecting from between the edges of the folded top closure flaps and in side by side relation, the said projecting portions being folded upon one of the top closure flaps and the collapsed portions projecting at the ends of said top closure flaps being folded inwardly over the end edges thereof.

5. In a package, the combination of an outer container member comprising side walls and bottom and top closure flaps, the side walls having

aligned fracturing zones adjacent to but spaced from the top end thereof, an inner container member comprising side walls, bottom closure flaps and opposed non-overlapping top closure flaps, said inner container member being adapted to be telescoped within the outer container member, and a bag of flexible material inserted in said inner container member with its top end when open projecting substantially beyond the said inner container member top closure flaps whereby said top closure flaps may be folded oppositely upon the sides of the bag with end portions thereof projecting from between the edges of the folded top closure flaps and in side by side relation, the said projecting portions being folded upon one of the top closure flaps and the collapsed portions projecting at the ends of said top closure flaps being folded inwardly over the edges thereof, the end closure flaps of the outer container being closed over the closed bag, the outer container member being fracturable along said fracturing lines to permit access to the contents of the package without opening said outer container top closure flaps, the portion of the inner container member projecting above the fracturing zone of said outer container member constituting a neck for detachably receiving the severed portion of the outer container which constitutes a removable cap.

6. In a package, the combination of an outer container member comprising side walls and bottom and top closure flaps, an inner container member comprising side walls, bottom closure flaps and opposed non-overlapping top closure flaps, said inner container member being adapted to be telescoped within the outer container member, and a bag of flexible material inserted in said inner container member with its top end when open projecting substantially beyond the said inner container member top closure flaps whereby said top closure flaps may be folded oppositely upon the sides of the bag with end portions thereof projecting from between the edges of the folded top closure flaps and in side by side relation, the said projecting portions being folded upon one of the top closure flaps and the collapsed portions projecting at the ends of said top closure flaps being folded inwardly over the edges thereof.

7. In a package, the combination of an outer container member comprising side walls and bottom and top closure flaps, the side walls having aligned fracturing zones adjacent to but spaced from the top end thereof, an inner container member comprising side walls and non-overlapping top closure flaps, said inner container member being adapted to be telescoped within the outer container member and having projecting tongues struck out from its walls constituting retaining members coacting with walls of the outer container member for retaining the inner container member in telescoped relation therein, and a bag of flexible material inserted in said inner container member with its top end when open projecting substantially beyond the said inner container member top closure flaps whereby said top closure flaps may be folded oppositely upon the sides of the bag with end portions thereof projecting from between the edges of the folded top closure flaps and the said projecting portions thus folded upon one of the top closure flaps and the portions of the bag projecting at the ends of said top closure flaps folded inwardly over the end edges thereof, the outer container member being fracturable along said fracturing lines to

permit access to the contents of the package without opening said outer container top closure flaps, the portion of the inner container member projecting above the fracturing zone of said outer container member constituting a neck for detachably receiving the severed portion of the outer container which constitutes a removable cap.

3. In a package, the combination of an outer container member comprising side walls and bottom and top closure flaps, an inner container member comprising side walls and non-overlapping top closure flaps, said inner container member being adapted to be telescoped within the outer container member and having projecting tongues struck out from its walls constituting retaining members coacting with walls of the outer container member for retaining the inner container member in telescoped relation therein, and a bag of flexible material inserted in said inner container member with its top end when open projecting substantially beyond the said inner container member top closure flaps whereby said top closure flaps may be folded oppositely upon the sides of the bag with end portions thereof projecting from between the edges of the folded top closure flaps, and the said projecting portions thus folded upon one of the top closure flaps and the portions of the bag projecting at the ends of said top closure flaps folded inwardly over the end edges thereof.

9. In a package, the combination of an outer container member comprising side walls and bottom and top closure flaps, the side walls having aligned fracturing zones adjacent to but spaced from the top end thereof, and an inner container member adapted to be telescoped within the outer container member and having projecting tongues

struck out from its side walls adjacent the bottom thereof, said tongues being hingedly connected at the bottom thereof and free at the top thereof and constituting bendable retaining members co-acting with the walls of the outer container member for lockingly retaining the inner container member in telescoped relation therein, said outer container member being fracturable along said fracturing lines, the severed portion of the outer container member constituting a cap, the portion of the inner container member projecting above the fracturing zone of the outer container member constituting a neck for detachably receiving the cap.

10. In a package, the combination of an outer container member comprising side walls and bottom and top closure flaps, the side walls having aligned fracturing zones adjacent to but spaced from the top end thereof, and an inner container member adapted to be telescoped within the outer container member and having projecting tongues struck out from its walls, said tongues being shaped for wedging engagement when moved into the outer container and for locking engagement when removed therefrom and constituting retaining members coacting with the walls of the outer container member for lockingly retaining the inner container member in telescoped relation therein, said outer container member being fracturable along said fracturing lines, the severed portion of the outer container member constituting a cap, the portion of the inner container member projecting above the fracturing zone of the outer container member constituting a neck for detachably receiving the cap.

KENNETH T. BUTTERY.
